UNITED STATES PATENT OFFICE.

GEORGE W. VAN NOSTRAND, OF GREENE, NEW YORK

MAIL-TRANSFERRING DEVICE.

1,150,909.

Specification of Letters Patent. Patented Aug. 24, 1915.

Application filed January 10, 1913. Serial No. 741,316.

To all whom it may concern:

Be it known that I, GEORGE W. VAN NOSTRAND, a citizen of the United States, residing at Greene, in the county of Chenango and State of New York, have invented new and useful Improvements in Mail-Transferring Devices, of which the following is a specification.

This invention relates to the class of mail bag catchers and deliveries.

The primary object of the invention is to provide a mail bag catcher and deliverer wherein the mail bags are carefully yet instantly and automatically transferred from either a moving train to a suitable stationary structure or from a stationary structure to a movable train, or both.

Another object of the invention is to provide a device of this character wherein the speed of the moving train will in no way affect the utility thereof, as the mail bags or sacks are handled in such a novel and peculiar manner as to render the transfer absolutely certain, instantaneous and automatic.

25 A further object of the invention is to provide a specially devised catch or gripping member, wherein the mail bag when once transferred is securely held in such a way as to render accidental loss or removal thereof impossible.

With the above and various other objects in view the invention consists essentially in the provision of a plurality of receptacles, certain of which are carried by a moving train, the others being supported by a suitable stationary structure, the bag adapted to be transferred from one set of receptacles to the other during the passing of the train.

40 Certain other features of construction together with the combination and arrangement of the several parts as will be herein-after fully described and specifically pointed out in the appended claim must be reasonably considered in determining the advantages and novel features of this invention.

In describing my invention in detail reference will be had to the accompanying drawings, wherein like characters denote like or corresponding parts throughout the several views, and in which:—

Figure 1 is a top plan view of the device, the car and stationary supporting structure being shown in section. Fig. 2 is a side elevation, the bags being in a position ready to be transferred.

Referring now more particularly to the

drawings wherein is illustrated the preferred form of my invention the numeral 1 designates a railway mail car of any desired type, having the usual door opening 2 therein, while the numeral 3 designates the stationary supporting structure.

The door 2 is provided with two mail bag receptacles, the upper receptacle 4 adapted to receive the mail during the transfer thereof, while the lower receptacle 5 is adapted to deliver the mail during such transfer. The stationary supporting structure 3 is likewise provided with an upper and lower mail bag receptacle, the upper receptacle 6 thereof being in detail a duplicate of the lower receptacle 5 of the car and the lower receptacle 7 being a duplicate of the upper receptacle 4. The two car receptacles being mounted upon the side of the car door opening in such a manner as to cause the upper receptacle 4 to pass beneath the upper receptacle 6 of the stationary supporting structure and the lower receptacle 5 of the car structure to pass above the lower receptacle 7 of the station structure, during the exchange of the mail bags or sacks from one receptacle to the other. Each of said receptacles being mounted in substantially the same manner the mounting of but one will be described in detail. Suitable brackets 8 are secured in any desired manner to the supporting means upon and between which is pivotally mounted a supporting rod 9, one end of which is provided with a flange 10, while the opposite end is provided with a suitable hand lever 11, thus holding the rod against lateral movement upon the brackets. The receptacle being rigidly secured to the rod 9 through the medium of a sleeve 12 formed integral therewith, and the lever being likewise rigidly secured thereto, it will be seen that the operation of the latter will cause the tilting or raising of the receptacle to a substantially vertical position, in which event the ejection of the mail bag or bags contained thereupon is permitted. A lug 13 is formed upon one bracket 8 in the path of the lever so that a contact between said lever and the lug is produced, thus limiting the movement of the latter as well as the receptacle.

When so desired, a pin 14 may be inserted within the opening 15 of the bracket beneath the lever when in normal position, thereby holding the receptacle incapable of being tilted until such pin has been removed.

The mail bag catching mechanism of the

two receiving receptacles 4 and 7 being in duplicate the detail construction of but one will be described. Each end of the receptacle is provided with a pointed tongue 16 projecting outwardly and slightly upwardly from the edge thereof, the under face of which is provided near its outer extremity with a loosely mounted link or retainer 17. A second tongue 18 also projects upwardly from the edge of said receptacle, in alignment with and directly beneath the tongue 16, the upper extremity of this tongue being bent as at 19 to form an abutment upon which the retainer 17 normally rests. The other or delivering receptacles 5 and 6 are also duplicated, each receptacle being provided with a pair of spaced apart spring arms 20 projecting outwardly from each end thereof.

20 In order to completely carry out my invention I have provided a loop or link 21, adapted to be secured in any suitable manner to the main bag or sack 22, shown in dotted lines in the drawings, a link being held by and between the arms 20 in such a manner as to depend or hang directly within the path of the pointed tongue 16.

The detail construction of the device having been fully described the operation thereof is as follows: The bags 22 are first placed one upon the delivering receptacle 5 and the other upon the receptacle 6, the link 21 fitting between the arms 20 so as to suspend or hang beneath the bottom face of the receptacle.

35 When so placed, it will be seen that the pointed tongue 16 of the receiving receptacles 4 and 7 are so positioned relative to the links 21 as to pass therethrough, in which event the bags are transferred one from the receptacle 6 to the receptacle 4 and the other from the receptacle 5 to the receptacle 7, the above being accomplished by the passing of the train.

From the above taken in connection with the accompanying drawings, it will be seen that the bags are automatically and instantaneously transferred without being subjected to the rough usage and handling ordinarily brought to bear thereupon, thus prolonging the usefulness of the bag; that when transferred the removal of the bags is accomplished by the operation of the lever; and that accidental loss or removal of the bags after transferred is also impossible, as the retainer so engages the abutment as to hold the link in proper place until purposely removed.

It is thought from the foregoing that the advantage and novel features of my device will be fully appreciated.

I desire it to be understood that I may make slight changes in the construction and in the arrangement and combination of the several parts, provided such changes fall within the scope of the subjoined claim.

Having thus fully described my invention, what I claim as new and desire to secure by Letters Patent, is:—

In a mail receiving apparatus, a receptacle, a receiving member affixed to the receptacle at one end thereof, said member comprising an angle arm disposed to extend forwardly of the receptacle, a straight arm mounted to extend in spaced relation to said angle arm, the mentioned arms being integral, an enlargement formed upon the straight arm at a point adjacent the free end, and a retaining element pivoted to depend from said angle arm and to engage with said enlargement to afford a locking means for the mail matter subsequent to transfer, substantially as described.

GEORGE W. VAN NOSTRAND.
